Primary Examiner — Charles D Hanson*(74) Attorney, Agent, or Firm* — Norris McLaughlin, PA**CLAIM**

The ornamental design for a revision stem and ball, as shown and described.

DESCRIPTION

FIG. 1 is a front perspective view of a revision stem and ball;
FIG. 2 is a first side elevational view thereof;
FIG. 3 is a second side elevational view thereof;
FIG. 4 is a rear side elevational view thereof;
FIG. 5 is a front side elevational view thereof;
FIG. 6 is a top plan view thereof; and,
FIG. 7 is a bottom plan view thereof.

Portions of the figures enclosed in broken lines form no part of the claimed design.

1 Claim, 7 Drawing Sheets See application file for complete search history.
